DAVID HALEY SMITH, OF BANKHEAD, ALBERTA, CANADA.

TOOL FOR REMOVING BOILER-SCALE.

1,177,363.

Specification of Letters Patent. Patented Mar. 28, 1916.

Application filed May 19, 1915. Serial No. 29,207.

To all whom it may concern:

Be it known that I, DAVID H. SMITH, a citizen of the United States, and a resident of Bankhead, in the Province of Alberta and Dominion of Canada, have invented a new and Improved Tool for Removing Boiler-Scale, of which the following is a full, clear, and exact description.

My invention relates more particularly to a pneumatic hammer for removing boiler scale, and it is so constructed that it can be used where it is impossible to work effectively and conveniently with chisel bars or a hand hammer.

The invention is characterized by a floating chisel positioned in the body of the pneumatic tool in front of the hammer, to be struck by the latter, the chisel being arranged to recede with the hammer under the pressure of the tool against the work. The body of the hammer is in two parts united by a threaded connection, the front member being in the form of a ring that clamps the cylinder and the cover plate thereof in position and serves to retain the floating chisel against displacement.

The invention will be particularly explained in the specific description following.

Reference is had to the accompanying drawings forming part of this specification, in which similar characters of reference indicate corresponding parts in all the views, and in which:

Figure 1 is a longitudinal section on the line 1—1 of Fig. 3; Fig. 2 is a similar view with the hammer and chisel in different positions in Fig. 1; and Fig. 3 is a cross-section on the line 3—3 of Fig. 1.

In constructing a practical embodiment of my invention in accordance with the illustrated example, the body of the tool is in two separate members, the back member 10 forming the cylinder of the pneumatic hammer and being united to the front end 11 thereof by a threaded connection as at 12.

At one side of the body is a tubular handle member 13 which in practice will receive a handle of proper length and shape for the convenient manipulation of the tool.

Within the body is a cylindrical bushing 14 in which operates a piston presenting upper and lower piston heads 15, 15^a. A front cover plate 16 is clamped at the front of the cylindrical bushing between the body sections 10, 11, said cover plate being en-

gaged by an annular internal shoulder 17 on the front ring section 11 of the body. In front of the cover plate 16 is a floating chisel 18 presenting suitable cutting members 19 on its working face, there being an annular flange 20 on the chisel outside of the working face, in the rear thereof, which is retained against displacement by an internal annular flange 21 on the body section 11.

The cover plate 16 has a central opening 22 through which the hammer 23 carried by the piston is adapted to be operated to deliver a blow against the inner face of the chisel 18. The said chisel has a limited reciprocating movement between the front plate 16 and the flange 21 and is adapted to be projected beyond the body by a blow of the hammer 23 when the front of the body and the working face of the tool are pressed against a side of the boiler surface to remove the scale from the latter. The pressure of the tool against the work will cause the floating chisel to recede as the hammer recedes and be in a position to receive an effective blow of the hammer on the forward strike of the latter.

Any approved arrangement of inlet ports and exhaust ports may be provided in the cylindrical bushing 14, to be controlled by the piston acting as a valve. In the illustrated form an annular chamber 24 between the front and rear piston heads 15, 15^a is in communication with the tubular handle member 13, which is connected in practice with a compressed air supply or equivalent source of fluid pressure. The bushing 14 is formed with a lateral port 25 which communicates with a rearwardly extending port 26 which in turn communicates with a lateral port 26^a leading to the rear side of the back piston head 15^a. A second transverse port 27 leads from the cylinder and a forwardly extending port 28 leading from the port 27 communicates with a lateral port 28^a at the front of the piston head 15. The exhaust from the back of the piston head 15^a discharges through a lateral port 29^a and a forwardly extending exhaust port 29, which extends through the bushing and through the front cover plate 16 to discharge the exhaust through a passage 31 extending forwardly from the back of the chisel 18 to the front of the latter, so that the exhaust will serve to blow chipped scale from in front of the tool. In the present example there

is a depression 30 in the front of the cover plate 16 to which the exhaust passage 29 leads and an annular depression 30^a in the opposed rear face of the chisel surface to maintain communication between the exhaust port 29 and the passage port 31 in the chisel. The fluid from in front of the piston head 15 exhausts through the central opening 22 in the plate 16 when the chisel is in the rearward position and thus through the depressions 30, 31, and discharges to and through the passage 31.

In assembling the parts, the chisel is dropped into the body section 11. The cover plate 16 is then placed in the said body to lie on the annular shoulder 17 thereof, and the piston and cylinder bushing having been placed in position in the body section, the two sections are united by threaded connections 12. The arrangement permits of the ready dismembering of the tool for cleaning or for the repair or renewal of particular parts, the construction being particularly advantageous in permitting the ready sharpening of the chisel 18. The tool is particularly useful in many situations where the usual chisel bars and hand hammer cannot be used with convenience or advantage.

It is to be observed that the flange 20 has a beveled forward surface 20^a extending annularly around the same, and a reverse bevel 20^b rearward of said front bevel; also that the flange 21 of the casing section 11 has a bevel 21 mating the bevel 20^a of the chisel. These beveled surfaces allow the floating chisel freedom to accommodate itself, without binding or jamming, to varying conditions in working at different angles to the boiler plate.

40. Having thus described my invention, what I claim as new and desire to secure by Letters Patent, is:

1. A fluid operated tool comprising a body, a piston in said body carrying a hammer, a cylinder in the body in which the piston operates, said cylinder having ports for the inlet and exhaust of a motive fluid, and a floating chisel separate from and in front of the hammer and arranged to have a reciprocating movement in the body and forming a closure of said body at the front, said working tool having a forwardly extending passage therethrough and in communication with the exhaust ports for the discharge of the exhaust fluid at the front of the chisel.

2. In a fluid operated tool, a body having separable front and back members and having a cylinder therein formed with inlet and exhaust ports, a piston in said cylinder having a longitudinally reciprocating hammer, a front cover plate for the cylinder through which the hammer is adapted to project when actuated in a forward direction, and a floating chisel in front of the cover plate

and hammer, adapted to receive blows of the hammer when the latter is projected through the cover plate, said chisel having unrestrained movement between said cover plate and the front member of the body, said cover plate being clamped by the said front member of the body, and the chisel being retained against forward displacement by the said front member.

3. In a fluid operated tool, a body having a tubular handle whereby to manipulate the tool and to conduct motive fluid thereto, a cylindrical bushing in the body engaging with the said tubular handle, said bushing being formed with inlet and exhaust ports, a piston operating in said bushing and carrying a hammer, a cover plate in front of the bushing and having openings communicating with the exhaust ports of the bushing, the cover plate permitting the hammer to project therethrough, and a floating chisel in front of the cover plate and hammer adapted to receive the blow of the latter and provided with a discharge passage for the exhaust.

4. In a tool of the character described, a body provided with means to supply a motive fluid, a cylindrical bushing in the body, a piston operating in the bushing and provided with a hammer, inlet ports communicating with the fluid supply and leading in opposite directions to the back and front of the piston, an exhaust port leading from the back of the piston forwardly, a cover plate having an exhaust port in communication with the exhaust port from the back of the piston and having a central opening through which the hammer projects, said opening forming an exhaust from the front of the piston when the hammer recedes, and a working tool in front of the hammer.

5. In a fluid operated tool, a body having separable front and back members and having a cylinder therein formed with inlet and exhaust ports, a piston in said cylinder having a hammer, a front cover plate for the cylinder through which the hammer is adapted to project, and a floating chisel in front of the cover plate and hammer, said cover plate and chisel being retained against displacement by the front member of the body, the floating chisel at the periphery thereof having reverse bevels extending around the same and the front member of the body presenting a beveled surface corresponding with the opposed bevel of the said chisel.

6. In a tool, a body, a hammer therein, means to reciprocate the hammer, and a reciprocating floating working tool held in the body separate from and in front of the hammer to be projected beyond the body by a blow of the hammer and adapted to have a receding movement under pressure of the work when the hammer recedes, said working

tool having a front working face, and being
tiltable to its general plane to accommodate
itself to different angular positions rela-
tively to the body to dispose its front work-
ing face in different planes to conform to the
surface of the work.

In testimony whereof I have signed my

name to this specification in the presence of
two subscribing witnesses.

DAVID HALEY SMITH.
